UNITED STATES PATENT OFFICE.

SALIM N. MALLOUK, OF BROOKLYN, NEW YORK.

DESIGN FOR A LACE TABLE COVER OR THE LIKE.

Application filed December 28, 1926. Serial No. 20,188. Term of patent 7 years.

To all whom it may concern:

Be it known that I, SALIM N. MALLOUK, a citizen of the United States of America, and a resident of the borough of Brooklyn, Kings County, city and State of New York, have invented a new, original, and ornamental Design for a Lace Table Cover or the like, of which the following description, in connection with the accompanying drawing, is a specification.

The single figure of the drawing is a plan view of one half of a lace table cover or the like, showing my new design, the representative portion of the illustration being repeated at the opposite end of the article.

I claim as my invention:

The ornamental design for a lace table cover or the like substantially as shown and described.

SALIM N. MALLOUK.
